UNITED STATES PATENT OFFICE.

HENRY C. TALLMADGE, OF CINCINNATI, OHIO.

DEVICE FOR TIGHTENING BANJO-HEADS.

SPECIFICATION forming part of Letters Patent No. 288,679, dated November 20, 1883.

Application filed February 19, 1883. (No model.)

To all whom it may concern:

Be it known that I, HENRY C. TALLMADGE, of Cincinnati, Hamilton county, Ohio, have invented a new and useful Improvement in 5 Brackets for Tightening the Heads of Musical Instruments, of which the following is a full, clear, and exact specification, reference being had to the accompanying drawings, forming part of this specification, in which—

10 Figure 1 is a vertical section of a banjo, showing attachment of bracket. Fig. 2 is a view of the separate parts of the bracket. Fig. 3 is a sectional view of the tube *b* of the bracket.

15 Similar letters of reference in the several drawings indicate the same parts.

My invention relates to devices for tightening the parchment heads of musical instruments; and it consists of a bracket having the 20 following parts: Referring to the drawings, Fig. 2, *b* is a tube having an interior screw-thread, as shown in Fig. 3, an exterior screw-thread cut on its lower edge, and a nut-like 25 enlargement, *b'*, near its upper end. The interior and exterior screw-threads run in opposite directions. *c* is a hook adapted to engage with the rim of a musical instrument. In Fig. 1 the hook *c* is shown attached to the rim *R* of a banjo. The hook *c* has on one side 30 a ring, *c'*, and is perforated by a screw-hole, *c''*. *d* is a screw-cap adapted to fit onto the lower end of tube *b*. *e* is an upper hook having a screw-thread cut on its shank and adapted to screw into tube *b*. *f* is a screw to be 35 screwed through the rim of the instrument and into hook *c* at *c''*.

My invention is used as follows: Referring to Fig. 1 of the accompanying drawings, the hook *c* is attached to the lower side of the rim 40 *R* by passing the screw *f* through the rim and into the hook *c* at *c''*. The tube *b* is then

passed through the ring *c'* of hook *c*, and the screw-cap *d* is screwed onto the tube below the ring *c'*. The tube *b* is free to turn in the ring *c'*, but the cap *d* prevents its withdrawal. 45 The upper hook, *e*, is then hooked over the upper side of the hoop on the rim *R*, and is screwed into the tube *b* by turning the said tube either with the fingers or by a wrench applied at the nut-like enlargement of the tube *b*. 50

Fig. 1 shows my bracket in position.

I am aware that screw-brackets for musical instruments have heretofore been made, and I do not claim the screw, broadly.

Having thus described my invention, what 55 I claim, and desire to secure by Letters Patent, is as follows :

1. A straining device for banjos, consisting of upper hook to engage with the small hoop, having screw-threaded shank, lower hook to 60 engage with the bottom of the large hoop, having eye *c'*, and the tube *b*, having nut-enlargement *b'*, engaging with and adjustable on the screw-threaded shank of the upper hook, and lower screw-threaded end provided with a 65 cap, *d*, and turning freely in the eye of the lower hook, as set forth.

2. The combination of upper hook, *e*, having screw-threaded shank, lower hook, *c*, having eye *c'*, screw-hole *c''*, and securing-screw 70 *f*, and the tube *b*, formed with nut-enlargement *b'*, for adjusting the upper hook, having screw-threaded lower end provided with cap *d*, and turning freely in the eye, as set forth.

The foregoing specification of my invention 75 signed by me this 8th day of February, A. D. 1883.

HENRY C. TALLMADGE.
